US00D603502S

(12) **United States Design Patent**
Petersen

(10) **Patent No.:** **US D603,502 S**
(45) **Date of Patent:** **** Nov. 3, 2009**

(54) **SURGICAL IMPACTOR**

(75) Inventor: **David A Petersen**, Clearwater, FL (US)

(73) Assignee: **Orthopedic Development Corporation**,
Clearwater, FL (US)

(**) Term: **14 Years**

(21) Appl. No.: **29/298,309**

(22) Filed: **Dec. 3, 2007**

(51) **LOC (9) Cl.** **24-02**

(52) **U.S. Cl.** **D24/133; D24/147**

(58) **Field of Classification Search** **D8/107, D8/300, 303, 307, 310, 311, 47, 14; D12/178, D12/179; 606/81, 91, 86 R, 99, 86 A, 86 B, 606/247, 79, 84; 32/167, 168; D24/133, D24/147, 146; 626/13.12; 600/567; D19/57, D19/58; 433/102**

FOREIGN PATENT DOCUMENTS

GB 2069761 10/1998

Primary Examiner—Jeffrey D Asch

Assistant Examiner—Anna J Burmeister

(74) *Attorney, Agent, or Firm*—Don J. Pelto, Esquire;
Sheppard Mullin Richter & Hampton, LLP

(57) **CLAIM**

I claim the ornamental design for a surgical impactor, as shown and described.

DESCRIPTION

FIG. 1 is a side view of a surgical impactor embodying my new design.

FIG. 2 is the opposite side view of a surgical impactor as compared to FIG. 1.

FIG. 3 is a top view of a surgical impactor embodying my new design; and,

FIG. 4 is a bottom view of a surgical impactor embodying my new design.

The broken lines in the drawings show environmental structure only and form no part of the claimed design.

1 Claim, 2 Drawing Sheets
